UNITED STATES PATENT OFFICE.

CHARLES H. WARREN, OF ATLANTA, GEORGIA, ASSIGNOR TO DRAPER COMPANY, OF HOPEDALE, MASSACHUSETTS, A CORPORATION OF MAINE.

THIN-PLACE-DETECTING MECHANISM FOR LOOMS.

No. 887,446.

Specification of Letters Patent.

Patented May 12, 1908.

Application filed September 7, 1907. Serial No. 391,766.

To all whom it may concern:

Be it known that I, CHARLES H. WARREN, a citizen of the United States, and a resident of Atlanta, in the county of Fulton and State 5 of Georgia, (whose post-office address is Atlanta, Georgia,) have invented an Improvement in Thin-Place-Detecting Mechanism for Looms, of which the following description, in connection with the accompanying drawing, 10 is a specification, like letters on the drawing representing like parts.

This invention relates to mechanism for detecting the occurrence of a thin place or streak in the cloth being woven on a loom and 15 to effect a change in the operation of the loom upon such detection. In such mechanism the detector or member has a depending end or finger which normally rests upon the cloth a short distance in front of the fell, 20 and such finger drops through the cloth when the thin place is reached. Sometimes this detecting action takes place when the lay is moving forward, and the front of the lay will strike the finger and bend it or otherwise injure the detecting mechanism.

My present invention has for its object the production of simple and efficient means to obviate injury to the thin-place detector by engagement with the lay.

30 The novel features of the invention will be fully set forth in the subjoined specification and particularly pointed out in the following claims.

The drawing represents a transverse sectional view of a sufficient portion of a loom having thin-place detecting mechanism, with one embodiment of my invention applied thereto.

40 The lay 1, breast-beam 2, temple 3, its stand 4, and the take-up or sand-roll 5 may be and are all of well-known or usual construction.

A stand 6 secured to the breast-beam is 45 extended rearwardly and provided with a transverse bearing 7 for a horizontal rock-shaft 8, the outer end of which is provided with a crank-arm 9, see dotted lines, which co-operates with a dog or pawl 10 pivotally connected at 11 with a shipper-releasing 50 lever 12.

Normally the dog is held in the position shown, but upon detection of a thin place in the cloth the rock-shaft 8 will be turned to lower the dog 10 into position to be engaged

by a vibrator 13, and thereby the operation 55 of the loom will be changed, such for instance as its stoppage by release of the shipper by or through the lever 12.

The inner end of the rock-shaft 8 is provided with an elongated, rearwardly extended arm 14 provided at its free end with a downturned portion or finger 15, constituting a thin-place detector and normally resting upon the cloth C in front of the fell.

When a thin place occurs the detector 65 drops, the finger 15 passing through the cloth, as shown in dotted lines, and in the path of the front of the lay should the latter be back of the finger when detection occurs. Obviously, in such case the front of the lay on its 70 forward beat will engage the depending end of the finger and will bend or break it, or otherwise damage the detecting mechanism. To prevent such injury I provide the lay with means to engage and lift the finger so that its 75 tip will pass across the raceway of the lay, and herein such means consists of a cam 16, formed by bending a strip 17 of metal, the strip being attached at 18 to the front of the lay.

80 The cam surface 16 is inclined upward and rearwards and as the lay comes forward the tip of the detector finger 15 will slide or ride up along the cam to the level of the raceway and across the same, absolutely preventing 85 any injury to any of the parts of the mechanism, as will be manifest.

I have shown a convenient form of thin-place detecting mechanism, but my invention is not restricted to such particular 90 mechanism, for it is applicable to any form wherein detecting action of the detector renders it liable to be engaged by the lay on its forward stroke.

Having described my invention, what I 95 claim as new and desire to secure by Letters Patent is:—

1. In thin-place detecting mechanism for looms, in combination, a detector to normally rest upon the cloth adjacent the fell, 100 a lay, and means thereon independent of the cloth to lift the detector from the path of the lay when the detector descends through the cloth into such path.

2. In thin-place detecting mechanism for 105 looms, in combination, a detector to normally rest upon the cloth adjacent the fell, a lay, and means on the front of the lay to

2
engage the tip of and lift the detector from the path of the lay when the detector has detected a thin place in the cloth.

3. In thin-place detecting mechanism for looms, in combination, a detector to normally rest upon the cloth adjacent the fell, a lay, and a cam mounted thereon and inclined upward and rearwards and adapted to engage the tip of the detector and lift the same to the raceway of the lay on its forward stroke when said detector has detected a thin place in the cloth.

4. In thin-place detecting mechanism for looms, in combination, a pivotally mounted, rearwardly extended detector having a depending finger to rest normally upon the

cloth in front of the fell, a lay, and a metallic member secured to the front thereof and provided with an upwardly and rearwardly inclined cam portion opposite the detector finger, to coöperate with the tip of the latter when passed through the cloth and lift said finger out of the path of the lay on its forward stroke.

In testimony whereof, I have signed my name to this specification, in the presence of two subscribing witnesses.

CHARLES H. WARREN.
